UNITED STATES PATENT OFFICE

EDWIN W. GOESER, OF LOS ANGELES, CALIFORNIA, ASSIGNOR TO EMSCO DERRICK & EQUIPMENT COMPANY, OF LOS ANGELES, CALIFORNIA, A CORPORATION OF CALIFORNIA

ROTARY DRAW WORKS WITH ADJUSTABLE JACK SHAFT

Application filed May 14, 1928. Serial No. 277,544.

This invention consists of a novel means for adjusting the position of a sprocket or a pair of sprockets or their equivalents, so that the endless member or members which extend around the sprocket or sprockets may have the proper tension. My invention is not only combinatively new in its entirety, but the combination of certain parts is new.

My invention has a particular utility on rotary draw works used in the oil well drilling industry, and in view of this I choose to illustrate my invention embodied in a rotary draw works.

In order that the utility and advantages of my invention may be fully appreciated, I shall briefly refer to the oil well drilling industry. The rotary draw works is mounted at one side of the derrick floor, and has a line shaft by which the spooling drum is driven. The type of draw works in which my invention is incorporated has a jack shaft which is mounted near the derrick floor below the line shaft. The line shaft operates the jack shaft by means of a sprocket and chain connection. The rotary table, which is situated near the center of the derrick floor, is driven by means of a sprocket and chain connection with the jack shaft. For best operating results the chains should be maintained at a certain tension.

It is an object of this invention to provide an adjustment means whereby a shaft or equivalent member may be repositioned by being moved at right angles to its axis.

Such an adjustment, when embodied in the jack shaft of the draw works, makes it possible to readily adjust the tension of either of the chains which is associated with it.

It is another object of this invention to provide an adjustment means whereby a shaft may be repositioned by being moved in two directions in planes at right angles to the axis of the shaft.

By incorporating this feature in the jack shaft of the rotary draw works, it is possible to adjust the tension on either or both of the chains associated therewith by repositioning the jack shaft.

A further object of this invention is to

provide an adjustment means for a shaft, the shaft being non-rotatable and rotatably supporting a pair of sprockets or their equivalent.

A still further object of my invention is to provide a combination which includes a rotatable member supporting a pair of sprockets or their equivalent, a shaft for supporting the rotatable member, and adjustment means for moving the shaft in two directions at right angles to the axis of the shaft.

Other objects will be pointed out in the following description of a rotary draw works which embodies my invention.

Referring to the drawings in which the rotary draw works is depicted,

Fig. 1 is a front elevational view of the rotary draw works.

Fig. 2 is a vertical cross-sectional view taken on the line 2—2 of Fig. 1.

Fig. 3 is an enlarged and vertical cross-sectional view taken on the line 3—3 of Fig. 1.

Fig. 4 is a cross-sectional view taken on the line 4—4 of Fig. 3.

Fig. 5 is a section showing the jack shaft assembly in section.

Referring specifically to the drawings, the draw works 10 embodying my invention includes a frame having uprights 11, 12, and 13, which extend between an anchor-base 15 and a head board 16 of a derrick, only a portion of which derrick is shown. This derrick forms part of a rotary drilling rig such as is adapted for use in drilling an oil well. The draw works 10 has a combined spooling and braking drum 20 rigidly mounted upon a rotatable shaft 21 which journals in suitable bearings provided on uprights 11 and 12. Rotatably mounted on the shaft 21 are sprockets 22, 23, and 24, any one of which is adapted to be non-rotatably locked to the shaft 21 by suitable clutch mechanisms. Extending across the draw works 10 above the spooling and braking drum 20, and journaled in suitable bearings provided upon uprights 11, 12, and 13, is a line shaft 25, which is adapted to be rotated by a sprocket 26 driven through a suitable sprocket chain from a

steam engine or other source of power. Sprocket pinions 27, 28, and 29 are non-rotatably mounted on the line shaft 25 and are connected by sprocket chains to the 5 sprockets 22, 23, and 24 respectively so that when any one of the latter three sprockets is non-rotatably connected to the shaft 21, this shaft and the spooling and braking drum 20 are rotated by the line shaft 25. The 10 different ratios between the diameters of the connected sprockets mentioned above make it possible to drive the shaft 21 by the shaft 25 at any one of three speed ratios.

Provided on opposite ends of the line shaft 15 are catheads 35 and 36, which are normally disposed at about the height of a man's head and are provided for drawing in upon a rope, loosely wound about one of these catheads by one of the workers. Rotatably 20 mounted on the line shaft 25, between the sprocket 29 and the upright 13, is a drive sprocket 40 which is adapted to be non-rotatably connected by a clutch 41 to the line shaft 25 by the operation of a suitable controlling 25 mechanism 42.

Constructed on the anchor base 15 is a derrick floor 45 and disposed parallel with and close to this floor is a jack shaft 46, the opposite ends of which are supported in 30 brackets 47 and 48 mounted on the lower ends of uprights 12 and 13 respectively. The jack shaft 46 is cylindrical and is provided with end portions 49, each having a flat lower face 50. The jack shaft end portions extend 35 across and are supported by the brackets 47 and 48. Each of these brackets includes a base member 55 which is connected by bolts 56 to one of the uprights 12 and 13. The base 55 extends outwardly and downwardly 40 to provide a clamp jaw 57 having a recess 58 which opens upwardly. The opposite side faces 59 and 60 of the recess 58 are preferably parallel to each other and this recess is open at both ends, as clearly shown in Fig. 4. 45 Suitable holes 60^a are provided in the jaw 57 for a purpose to be described later.

Resting in the recess 58 and supporting a plate 62, which has apertures aligned with holes 60^a, is a plurality of shims 63. The end 50 portions 49 of the jack shaft 46 rest upon the central portion of the plates 62. Fitting over the end portions 49 of the jack shaft 46 are cavities 64 eccentrically provided in a pair of clamp means or caps 65. The caps 55 65 have holes 66 which are aligned with the apertures in the plates 62 and with the holes 60^a so that bolts 68 may extend upwardly through the holes 60, through the plates 62 and the holes 66, and bind the caps 65 against 60 the jack shaft ends 49 so as to rigidly position the jack shaft 46 upon the brackets 47 and 48.

As will be noted in Fig. 3, the eccentric cavities 64 are so formed that when the caps 65 are removed, turned 180° on a vertical axis,

and replaced over the jack shaft ends 49, the caps 65 are in the positions indicated by broken lines 70 in Fig. 3. This causes the jack shaft 46 to be moved a slight distance toward the uprights 12 and 13. Likewise, 70 by loosening the bolts 68, some of the shims 63 may be removed or additional shims inserted between the jaws 57 and the plates 62 so that when the bolts 68 are again tightened, the jack shaft 46 will be a greater or less distance than previously from the line shaft 25.

Rotatably mounted on the jack shaft 46 is a jack shaft sprocket member 72 having a driven sprocket 73 and a drive sprocket 74. 80 The jack shaft sprocket member is supported by a bearing 71. The driven sprocket 73 is in alignment with the sprocket 40 and connected thereto by a suitable sprocket chain 75.

Mounted in the center of the derrick floor 45 is a rotary table 78, which is adapted for rotating a drill pipe extending into the well. The rotary table 78 is adapted to be driven by rotation of a shaft 79 provided with a pinion sprocket 80. The sprocket 80 is in 90 alignment with the drive sprocket 74 of the draw works 10 and a sprocket chain 81 extends around and connects these sprockets.

The feature of my invention, as previously pointed out, is the adjusting means. In the present embodiment the tension of the chain 81 is adjusted by reversing the position of the caps 65 which moves the jack shaft 46 and the sprocket member 72 away from the sprocket 80. The tension of the chain 75 is adjusted by removing or inserting shims 63 which lowers or raises the jack shaft 46 and the sprocket member 72.

I claim as my invention:

1. In a rotary draw works the combination 105 of: a plurality of upright frame members; a line shaft rotatably mounted on upper portions of said members; a jack shaft; a drive sprocket on said jack shaft adapted to be connected by a sprocket chain with a rotary table for driving the same; means for driving said drive sprocket from said line shaft; brackets provided upon lower portions of said uprights and adapted to support said jack shaft, each of said brackets having an upwardly opening recess across which an end of said jack shaft extends; positioning means applicable to said jack shaft ends and fitting into said recesses of said brackets in a plurality of positions to vary the distance 115 between said jack shaft and said rotary table, the distance between said jack shaft and said line shaft, or both of said distances; and means for securing said positioning means to said brackets.

2. In combination: a first shaft; a second shaft; a third shaft; a first drive means associated with said first and third shafts; a second drive means associated with said second and third shafts; a base; a cap having 130

a non-central cavity in which said third shaft rests; means for securing said cap to said base in a normal or reverse position, thus rendering said cap and said third shaft adjustable 5 toward or from one of the other shafts; and shim means whereby said cap and said third shaft may be moved toward or from said base, thus giving an adjustment between said third shaft and the other of said first and 10 second shafts.

3. In a rotary draw works the combination of: a plurality of upright frame members; a line shaft rotatably mounted on upper portions of said members; a jack shaft; a 15 drive sprocket on said jack shaft adapted to be connected by a sprocket chain with a rotary table for driving the same; means for driving said drive sprocket from said line shaft; brackets provided upon lower 20 portions of said uprights and adapted to support said jack shaft; and means for mounting said jack shaft on said brackets, said mounting means being shiftable on said brackets to vary the distance of said drive 25 sprocket from said rotary table, the distance between said jack shaft and said line shaft, or both of said distances, and in which each of said brackets has a recess opening upwardly and across which an end of said jack 30 shaft extends, said mounting means including clamp members, one of which is adapted to fit into each of said recesses and to be thereby held against lateral movement, each of said clamp members having an offset cavity 35 fitting said jack shaft, said cavity changing its location relative to the bracket supporting that clamp member when said member is changed from one to another of a plurality of positions in which it fits into the 40 recess in that bracket.

In testimony whereof, I have hereunto set my hand at Los Angeles, California, this 4th day of May, 1928.

45

EDWIN W. GOESER.
